(57) CLAIM

The ornamental design for a grip for a writing instrument, as shown and described.

DESCRIPTION

FIG. 1 is a front, right perspective view of a grip for a writing instrument showing our new design;

FIG. 2 is a front, right perspective view thereof with the grip in a twisted state;

FIG. 3 is a front elevational view of FIG. 1;

FIG. 4 is a rear elevational view of FIG. 1;

FIG. 5 is a right side elevational view of FIG. 1;

FIG. 6 is a left side elevational view of FIG. 1;

FIG. 7 is a top plan view of FIG. 1; and,

FIG. 8 is a bottom plan view of FIG. 1.

The broken line showing of a writing instrument in FIGS. 1-8 is environmental only and forms no part of the claimed design.
